UNITED STATES PATENT OFFICE.

EDWARD J. YOUNG, OF HAVERHILL, MASSACHUSETTS, ASSIGNOR, BY DIRECT AND MESNE ASSIGNMENTS, TO UNITED SHOE MACHINERY COMPANY, OF PATERSON, NEW JERSEY, A CORPORATION OF NEW JERSEY.

TACK-SAVER FOR LASTING-MACHINES.

1,030,220.

Specification of Letters Patent. Patented June 18, 1912.

Application filed April 20, 1908. Serial No. 428,012.

To all whom it may concern:

Be it known that I, EDWARD J. YOUNG, of Haverhill, county of Essex, State of Massachusetts, have invented an Improvement 5 in Tack-Savers for Lasting-Machines, of which the following is a specification.

This invention relates to tack saving attachments for lasting machines, more especially those of the character known as hand 10 method machines, in which the operator holds a shoe to be lasted by hand in position to be acted upon by the tack driving and lasting devices, machines of this general character being disclosed in the U. S. Patents #510,873, 15 and #584,741, and my attachment being especially designed to be applied to an improved form of said machine, which is now in general use and which will be hereafter more fully described.

20 While machines of this character are provided with clutch mechanism for starting and stopping the machine, the ordinary operator frequently fails to stop the machine coincidently with the removal of the shoe 25 therefrom, and he can, moreover, perform his work with less effort if he permits the machine to run while he is changing the shoe from one position to another. The result is that a large number of tacks are 30 wasted in the ordinary operation of the machine.

The object of my invention is to provide a simple device which may be readily attached to a lasting machine of the character 35 now in general use, and more particularly hereinafter described, and which is adapted to control the operation of the tack separating and feeding mechanism, so that the feeding of the tacks will be instantly 40 stopped upon the withdrawal of the shoe from the machine, and will be immediately started upon the placing of the shoe in position to receive the tacks. I accomplish this object by the means shown in the accompanying drawing, in which,

Figure 1 is a side elevation of a portion of a lasting machine provided with my invention, only such parts being shown as directly coöperate with my attachment. Fig. 50 2 is a detail view of the driver cam and the

portion of the driver which engages it. Figs. 3 and 4 are detail plan views and Figs. 5 and 6 are detail side views of my attachment and the parts directly coöperating therewith, said parts being shown in 55 different positions to illustrate the operation.

In the drawing *a* indicates the frame of the machine having the main driving shaft *b*, which is adapted to be continuously rotated by the pulley *c*. The tack driving mechanism comprises a driver *d* adapted to reciprocate in the holder *e* and to be lifted against the action of a torsion spring *f*, by means of a cam *g*¹⁰ on the end of the shaft *b*, 60 the cam releasing the driver at a certain point, to permit it to be forced downwardly by the spring. The main or tack-carrying slide *h* is mounted in the frame to slide parallel to the shaft *b*, and is adapted to be reciprocated by means of the lever *i*, which is oscillated by the cam *j* on the shaft *b*. The slide *h* is provided with an inclined projection *h'*, which is adapted to engage a wheel *k* mounted on a lever *m* pivoted at *n*, so 65 that, as the slide is advanced from its rearmost to its foremost position, it swings out said lever against the action of a spring *z*. An operating lever *o*, having a gear segment *o'* at one end and an arm *o*² at the other, is 70 also pivoted upon the pivot *n*, and a spring *x* is interposed between the lever *m* and arm *o*², at one side of pivot *n*. A stop screw *y* is mounted in lever *o*, at the other side of 75 said pivot in position to engage a shoulder *m'*, on lever *m*, at the same side of said pivot. As the spring *z* acts to return lever *m* after it has been forced outwardly by the cam projection *h'*, when said lever *m* is oscillated, it will swing lever *o* in one direction, through the action of spring *x*, and return it by engagement with screw *y*. Said levers *m* and *o* thus, under normal conditions, oscillate as one lever. A tack race-way *p*, which leads from a suitable magazine or source of supply, not shown, is provided, and a tack separator *q*, having a separating finger *q'*, is secured on a reciprocally mounted block *q*⁰, at the end of the race-way, said block having a rack *u* in 80 85 90 95 100

mesh with the segment o' of lever o , so that when the lever o is oscillated the separator will be reciprocated thereby. In the withdrawn position of the separator the end of its slot q^2 is opposite the mouth of the race-way, so that a tack may enter it, and as the separator is advanced its finger q' passes between this tack and the next tack, preventing the escape of any more tacks until it is again withdrawn. The first tack is carried, as the separator advances, into the tack hole q^3 , at which point it will drop into the tack-holder r mounted on the front end of the slide h . As the separator is advanced the slide h is retracted so that the latter is in its retracted position when the separator drops the tack therein. The separator is withdrawn as the slide advances from the tack-receiving position of Fig. 3 into the position for driving of Fig. 4, and the driver is released, forcing the tack from the holder and driving it. In the forward movement of the slide, the lever m is moved from the full line position of Fig. 3, to the dotted position thereof in said figure withdrawing the separator, so that the next tack will enter the mouth of the slot q^2 thereof. The separator, therefore, closes the raceway at all times, except when it is opened, in the withdrawn position of the separator, to permit one tack to pass into the separator slot.

The machine, as thus far described, forms no part of my invention, and, as the lasting mechanism which is associated therewith practically in no way modifies or co-operates with my attachment, such mechanism is not described, the lasting pincers s being merely shown in Fig. 1 to indicate the character of the machine.

According to my invention I provide a lever 1 , which is mounted to swing vertically on a pivot 2 , on some stationary part of the machine, as shown, or upon an independent support. A rod 3 passes through the front end of lever 1 and is secured therein by means of a set screw 4 , so that it may be vertically and rotatably adjusted therein, and an arm $3'$ extends therefrom nearly horizontally and has a friction roll 5 at its end. A spring 6 is connected to the lever 1 at the opposite side of pivot 2 from the arm $3'$, and acts normally to hold the end of lever 1 , to which it is attached, in an elevated position, correspondingly depressing the arm $3'$. The end portion of lever 1 , at the same side of the pivot 2 as the spring 6 , is provided with a rod shaped extension $1'$, on which a finger 7 is adjustably mounted, said finger 7 being adapted to be moved longitudinally and swing vertically on said extension and having a suitable means for clamping it in different positions thereon. Said finger 7 extends at approximately right angles to said lever 1 , and is provided with

an upturned end portion or toe 8 , as best shown in Figs. 5 and 6, and said finger 7 is so adjusted that, when lever 1 is held in its normal position by spring 6 , said toe 8 will engage the outer side of the short arm o^2 of the lever o , opposite the spring x , in which position it is adapted to prevent the outward swinging of said arm o^2 on said pivot n , when the lever m is thrown outwardly by the slide h , as it advances. The spring is adapted to be compressed sufficiently to permit said lever m to be swung outwardly, to its fullest extent, so that, while the toe 8 is in the position of Figs. 3 and 5, the lever o will be prevented from oscillating, and, therefore, the separator will be held stationary and no tacks will be fed to the tack carrier.

When the shoe is placed in position in the machine, that is, is held against the under side of the tack carrier, its sole will be pressed up against the roll 5 on arm 3 , lifting said arm from the position of Fig. 5, to the position of Fig. 6, drawing the toe 8 down below the level of the end portion o^2 , of the lever o , so that the attachment is practically entirely disengaged from the machine, permitting the lever o to be actuated upon the advance of the lever m and the separator to be operated. As soon as the shoe is withdrawn, the spring 6 again lifts the toe 8 in front of the arm o^2 , again preventing operation of the separator.

From the foregoing description it will be apparent that while the shoe is held in position, the machine will operate in the ordinary manner, the roll 5 running easily on the sole when the shoe is moved while in engagement therewith, so that the attachment does not interfere with the work of the operator, and, when the shoe is removed, further feeding of the tacks will be immediately prevented. The arm $3'$ is adapted to be adjusted to various positions to meet different requirements.

Having thus described my invention, what I claim as new and desire to secure by Letters Patent is:—

1. In a lasting machine, the combination of a main shaft, the driver, the tack holder, and tack feeding devices comprising a tack race-way and tack separator, said separator being movable in opposite directions to feed the tacks separately from the race-way to the tack-holder, an operating device movable back and forth to operate said separator, a spring located between said shaft and said operating-device, means operated by said shaft for compressing said spring to move said operating device in one direction, a locking device having an abutment and means for normally holding said abutment in the path of movement of said operating device to prevent movement thereof upon

compression of said spring, and an arm connected to said locking device and disposed to be engaged by the shoe when placed in position in the machine to move said abutment out of engaging position, substantially as described.

2. In a lasting machine, the combination of the main shaft, the driver, the tack holder, and the tack feeding devices comprising a tack race-way, and a tack separator movable to deliver the tacks separately from the race-way to the holder, connections between said shaft and said separator for operating the separator as the shaft rotates, locking means for the separator normally acting to prevent operation thereof by the shaft, an engaging device having a horizontally and vertically adjustable arm connected thereto, adapted to be engaged by the shoe when held in position in the machine and to be moved thereby to cause the engaging device to release the separator and permit the same to be operated by the shaft, substantially as described.

25 3. In a machine of the class described, the combination with tack-delivering devices and means for actuating said devices, of means controlled by the position of the work for locking the delivering devices with a tack therein ready to be delivered when the devices are unlocked.

4. In a machine of the class described, the combination with tack-delivering devices, a spring, and means, acting through said spring, for actuating said devices, of means, controlled by the position of the work, for locking the delivering devices with a tack therein ready to be delivered when the devices are unlocked.

40 5. In combination, a movable work rest, a tack feed slide, and means for controlling the movement of said slide, said means having one end connected with the work rest and its other end free to be thrown into position to lock the feed slide in tack delivering position.

6. A machine of the class described having, in combination, a tack driver, a reciprocating tack carrier, a tack raceway, a tack separator, a two part lever the members of which are yieldingly connected and one of which members has operative connection with the separator to reciprocate it, a cam on the carrier to engage the other member of the lever to move the lever in one direction, a spring to return the lever, and means arranged to be controlled by the shoe as the shoe is moved out of tack receiving position to engage the lever member which is connected with the separator and stop the reciprocation of the separator.

7. A machine of the class described having, in combination, a tack driver, a reciprocating tack carrier, a tack raceway, a tack

separator, a two part lever the members of which are yieldingly connected and one of which members has operative connection with the separator to reciprocate it, a cam on the carrier to engage the other member of the lever to move the lever in one direction, a spring to return the lever, a control lever having its front end in position to be lifted by the shoe and extending along the side of the machine toward said two part lever, a finger on the control lever having a toe which, when the shoe is not in contact with the control lever, stands in the path of the lever member that is connected with the separator.

8. A machine of the class described having, in combination, a tack driver, a reciprocating tack carrier, a tack raceway, a tack separator, a two part lever the members of which are yieldingly connected and one of which members has operative connection with the separator to reciprocate it, a cam on the carrier to engage the other member of the lever to move the lever in one direction, a spring to return the lever, and means arranged to be controlled by the shoe as the shoe is moved out of tack receiving position to lock the separator against return movement after it has moved into tack delivering relation to the carrier.

9. A machine of the class described having, in combination, a tack driver, a reciprocating tack carrier, a tack raceway, a tack separator, connections from the carrier to the separator to reciprocate the separator between receiving relation to the raceway and delivering relation to the carrier, and means controlled by the work to stop the separator in delivering relation to the carrier.

10. A machine of the class described having, in combination, a tack driver, a reciprocating tack carrier, a tack separator, operating connections between the carrier and the separator, a shoe rest support arranged at one side of the path of the tack carrier and a shoe rest rod having a laterally bent portion carrying a shoe bottom engaging member, said rod being adjustable rotatably in its support.

11. A machine of the class described having, in combination, a tack driver, a reciprocating tack carrier, a tack separator, operating connections between the carrier and the separator, a shoe rest support arranged at one side of the path of the tack carrier and a shoe rest rod extending from said support downwardly and laterally to a point in front of the carrier and having a roll on its end portion for contact with the shoe.

12. A machine of the class described having, in combination, a tack driver, a reciprocating tack carrier, a tack separator, operating connections between the carrier and

4
the separator, a shoe rest rod having a portion extending approximately parallel with the plane of the shoe bottom and at an oblique angle to the vertical plane in which the carrier reciprocates and a shoe bottom engaging roll arranged to turn on said portion of the rod as an axle.

In testimony whereof, I have signed my name to this specification, in the presence of two subscribing witnesses.

EDWARD J. YOUNG.
